UNITED STATES PATENT OFFICE.

FRANK McFARLAND, OF MEXICO, MISSOURI.

ALLEVIATOR FOR HYDRAULIC APPARATUS.

Application filed October 18, 1926. Serial No. 142,459.

This invention relates to devices of the kind commonly termed alleviators that are used in connection with hydraulic pumps, flow lines and other kinds of hydraulic apparatus for reducing the force of discharge of a liquid that is being pumped or for maintaining a substantially uniform rate of discharge of liquid from or through an hydraulic apparatus.

10 My present invention is an improvement on the invention that forms the subject-matter of my United States Patent No. 1,590,587, dated June 29, 1926, for pneumatic alleviators for hydraulic pumps, and has for its 15 main object to provide an alleviator of novel construction, which is of such design that it is impossible for the medium confined between the upper end of the plunger and the upper end of the cylinder of the alleviator 20 to leak downward through the plunger and escape from the cylinder when the pump or other apparatus with which the alleviator is used is idle or not operating.

Figure 1 of the drawings is a top plan 25 view of an hydraulic pump equipped with an alleviator embodying my present invention; and

Figure 2 is an enlarged vertical sectional view of said alleviator.

30 In Figure 1 of the drawings A designates a conventional hydraulic pump whose discharge pipe 1 is provided with an alleviator of the general type disclosed in my United States patent previously referred to. Said 35 alleviator comprises a cylinder formed preferably from a base portion 2 and a top portion 3 detachably connected together by fastening devices 4, and a plunger 5 reciprocatingly mounted in said cylinder. The 40 cylinder is provided at its lower end with an opening 6 that establishes communication between the interior of the cylinder and the discharge pipe 1 of the pump, and the plunger 5 is preferably hollow and provided 45 at its lower end with a reduced extension 7 that constitutes a dash pot element which enters the opening 6 in the lower end of the cylinder as the plunger 5 nears the end of its downward stroke. A medium is confined 50 between the upper end of the plunger and the top wall of the cylinder of the alleviator so as to exert downward pressure on the plunger in opposition to the upward pressure exerted on the plunger by the liquid 55 being pumped, which medium will usually

consist of oil α and air that is trapped between the upper end of the cylinder and the surface of said body of oil.

In order to prevent said medium from leaking from the cylinder a packing 8 is arranged between the exterior of the plunger 5 and the bottom portion 2 of the cylinder, and a separate packing 9 is arranged at the upper end of the bottom portion of the cylinder so as to surround the top portion 3 of the cylinder.

As previously stated, the main object of my present invention is to provide an alleviator which is of such construction that it is impossible for the oil or air in the upper portion of the cylinder to leak downwardly around the plunger 5 when the pump or other apparatus with which the alleviator is used is standing idle.

To this end I provide the lower end of the cylinder with an imperforate seat 10 that surrounds the opening 6 therein, and provide the lower end of the plunger 5 with a gasket 11 that bears tightly against said seat 10 when the plunger is at the end of its downward stroke, thereby effectively sealing the lower end of the cylinder of the alleviator. When the plunger 5 moves downwardly any liquid from the discharge pipe of the pump that may be in the space between the seat 10 on the end wall of the cylinder and the opposed lower end of the plunger 5 is expelled from said space and forced back into the discharge pipe through the joint between the reduced extension 7 on the plunger and the side wall of the hole 6 in the end wall of the cylinder which receives said extension, the extension 7 having a loose fit in the hole 6.

It is immaterial, so far as my broad idea is concerned, how the extension or dash pot element 7 is combined with the plunger 5, but in order to simplify the construction and reduce the cost of manufacture of the alleviator, I prefer to form said extension from a member separate and distinct from the plunger and provide said member with a reduced externally-screw-threaded portion 7^a that is screwed into the lower end of the plunger 5. The gasket 11, previously referred to, is preferably formed of fibre and is so proportioned that the inner portion of same will be clamped between the end of the plunger 5 and the dash pot element 7 on the plunger, as such a construc-

tion insures the gasket 11 being held securely in operative position on the plunger and permits said gasket to be replaced easily.

Having thus described my invention, what I claim as new and desire to secure by Letters Patent is:

1. In an alleviator of the kind that comprises a cylinder provided with a plunger that is acted upon by a medium confined between the upper end of the cylinder and the upper end of the plunger, an opening in the lower end of the cylinder, a reduced extension at the lower end of the plunger constructed so as to constitute a dash pot element that enters said opening when the plunger is at the end of its downward stroke, and means for producing a tight joint between the lower end of the cylinder and the lower end of the plunger that surrounds the dash pot element on the plunger.

2. In an alleviator of the kind that comprises a cylinder provided with a plunger that is acted upon by a medium confined between the upper end of the cylinder and the upper end of the plunger, an opening in the lower end of the cylinder, a reduced extension at the lower end of the plunger constructed so as to constitute a dash pot element that enters said opening when the plunger is at the end of its downward stroke, a flat seat on the lower end wall of the cylinder which surrounds the opening in said wall, and a gasket at the lower end of the plunger surrounding the dash pot element thereon and adapted to press against said seat when the plunger is at the end of its downward stroke.

3. In an alleviator of the kind that comprises a cylinder provided with a plunger that is acted upon by a medium confined

between the upper end of the cylinder and the upper end of the plunger, an opening in the lower end of the cylinder, a reduced extension at the lower end of the plunger constructed so as to constitute a dash pot element that enters said opening when the plunger is at the end of its downward stroke, a flat seat on the lower end wall of the cylinder which surrounds the opening in said wall, and a gasket at the lower end of the plunger surrounding the dash pot element thereon and adapted to press against said seat when the plunger is at the end of its downward stroke, said dash pot element having a loose fit in the opening in the end wall of the cylinder so as to provide for the escape of the liquid from the space between said end wall and the opposed end of the plunger when the plunger approaches the end of its downward stroke.

4. An alleviator of the kind referred to, comprising a cylinder provided at its lower end with an opening that establishes communication between the interior of the cylinder and the apparatus on which the alleviator is mounted, a reciprocating plunger in said cylinder whose upward movement increases the pressure of a medium confined between the upper end of the plunger and the top wall of said cylinder, a dash pot element at the lower end of the plunger formed from a member provided with a reduced portion that is screwed into the plunger, a flat seat surrounding the opening in the lower end of the cylinder, and a gasket on the plunger confined in position by said dash pot element and adapted to bear against the seat at the lower end of the cylinder.

FRANK McFARLAND.
